FOOTWEAR

Edwin Calvin, Akron, Ohio

Application April 21, 1937, Serial No. 133,203

3 Claims. (Cl. 36—17)

This invention relates to footwear.

Heretofore in the manufacture of footwear, constructions have been provided which include an upper with an in-sole, a mid-sole secured to the upper as by McKay stitching, nailing, or cementing, and an out-sole secured to the mid-sole as by Goodyear stitching, nailing or cementing, no welting, as such, being employed. The mid-soles heretofore used have been of various materials such as fiber-board, leather, rubber, etc.

Rubber mid-soles are highly desirable for various reasons. They are flexible and water-proof and give cushioning qualities to the footwear, but heretofore, they have not been entirely satisfactory for building into footwear and for use therein.

Rubber being flexible and elastic has a tendency to creep and crawl when it is attempted to sew, nail or cement it to the upper and to form a bulge inside of the stitches or nails or in the cemented joint; the edge of the mid-sole, which simulates the usual welting it displaces, becomes wavy and uneven, and although some of the bulging and unevenness of the mid-sole is eliminated by being flattened out when the out-sole is applied, this puts a strain upon the stitches or loosens the mid-sole retained by nails or cement under the spreading action of the rubber and causes early failure of the stitches when the footwear is in service. These difficulties have led to extensive use of less desirable material than rubber for mid-soles.

The present inventor has discovered that all of these difficulties may be overcome, rendering rubber mid-soles capable of effective use, both in application in footwear and in service, by providing rubber mid-soles with a stiffening insert of other materials of a flexible but somewhat stiffer nature. Inserts of sheet fibre, comparatively hard rubber, paper-board, etc., may be used as described herein to provide effective rubber mid-soles for footwear construction.

The general purpose of the invention, therefore, is to provide a footwear construction and method for making the same in which soft, elastic, vulcanized rubber mid-soles are used with which are associated inserts of more or less flexible but somewhat stiffer materials to produce the advantages therein which will be more particularly set forth in the succeeding paragraphs of this specification.

The foregoing and other purposes of the invention are attained in the footwear and by the method illustrated in the accompanying drawings and described below. It is to be understood

that the invention is not limited to the specific form thereof shown and described.

Of the accompanying drawings:

Figure 1 is a top plan view of a mid-sole embodying the invention. 5

Figure 2 is a section on line 2—2 of Figure 1.

Figure 3 is a bottom perspective view of footwear having the improved mid-sole applied thereto.

Figure 4 is a section on line 4—4 of Figure 3, 10 in perspective.

Figure 5 is a perspective view of completed footwear embodying the invention.

Figure 6 is a section similar to Figure 4 through 15 footwear utilizing a prior form of rubber mid-sole and showing the bulge inside the stitches and the waviness of the edges of such mid-soles.

Referring to Figures 1 to 5 of the drawings, the numeral 10 designates a flexible cushion-rubber mid-sole embodying the invention. This mid-sole may be molded and vulcanized to the shape shown with upper marginal portions formed as at 11, 11 to simulate welting. An insert is shown at 12. The insert is preferably of less width than the mid-sole so as to come inside of the marginal portions of the mid-sole whereby it will not be exposed at the edge of the sole and preferably is confined to the ball portion of the mid-sole so that the shank 13 is highly flexible. This insert may be of fibre, card-board, comparatively hard 20 rubber or other semi-stiff flexible material. It may be applied to the top of the mid-sole as shown or to the bottom or in the body thereof and is preferably embedded and secured therein by vulcanization (see Figure 2) during the process 25 of forming and vulcanizing the mid-sole. It may also be perforated as indicated to interlock with the rubber of the mid-sole during vulcanization. 30

In application of the mid-sole to footwear, it may be first tacked or stapled as indicated at 14, 40 14 to the upper 15 (see Figure 3) and then stitched, as by McKay stitching 16 to the upper 15.

This stitching is preferably done through the sole about the edge of the stiffening element 12 (see Figure 4). Due to the presence of the 45 stiffener 12, the mid-sole is easily and effectively applied to the footwear and lies evenly and flatly against the bottom of the upper without bulges in the rubber inside the McKay stitches and the marginal portions of the mid-sole, even though 50 the stiffener is not extended therein, extend evenly and flatly, without waviness, laterally from the upper. Compare Figure 4 with Figure 6 showing the prior form of rubber mid-sole S which forms a bulge at B and a wavy edge at E, E, and which 55

when the out-sole is later applied spreads and throws an outward strain on the McKay stitches M, M.

The mid-sole may be secured to the upper by 5 nailing or cementing and because of the invention this is more easily and effectively accomplished than heretofore.

As shown in Figure 5, after application of the 10 mid-sole, an out-sole and a heel of leather may be applied, the out-sole being indicated at 17 and the heel at 18. The out-sole may be applied by Goodyear stitching 19 through the out-sole and the marginal portions 11 of the in-sole outside of the upper. The heel may be nailed onto the shoe 15 in the usual way. An out-sole of rubber or other desired material may be applied to the mid-sole either by Goodyear or like stitching or by cementing, a cemented joint being improved with the new mid-sole by reason of the elimination of 20 bulges and waviness preventing spreading and creeping actions tending to cause separation.

Modifications of the invention, other than those which are disclosed herein, may be resorted to

without departing from the spirit thereof or the scope of the appended claims.

What is claimed is:

1. Footwear comprising an upper, a mid-sole and an out-sole, said mid-sole comprising a flexible, elastic, material having associated therewith a reinforcing sheet of comparatively stiff, semi-flexible material centrally thereof, said mid-sole being sewn to the upper and having a marginal portion extending outwardly thereof formed on 10 its upper surface to simulate welting and being unreinforced, and said out-sole being sewn to the mid-sole through the marginal portion of the mid-sole about the upper.

2. Footwear as set forth in claim 1, said semi- 15 flexible material being confined to the ball portion of the sole.

3. Footwear as set forth in claim 1, said semi-flexible material being of such extent and so positioned as to be inside of the marginal portions 20 of the mid-sole and said mid-sole being sewn to the upper and out-sole through said marginal portions of the sole about said material.

EDWIN CALVIN.
